MASTER TESTING CARD FOR JACQUARD KNITTING MACHINES

Filed Nov. 22, 1924

Frank King
By his Attorney
Marshall R. Sherwin

UNITED STATES PATENT OFFICE

FRANK HUG, OF BROOKLYN, NEW YORK, ASSIGNOR TO FRANKLIN KNITTING MILLS, INC., OF NEW YORK, N. Y., A CORPORATION OF NEW YORK

MASTER TESTING CARD FOR JACQUARD KNITTING MACHINES

Application filed November 22, 1924. Serial No. 751,570.

My present invention relates to master testing cards, more particularly master testing cards for use in connection with jacquard attachments for flat knitting machines and 5 also for flat knitting machines adapted to knit jacquard patterns into fabrics. It is an object of the present invention to produce a simple and efficient device which is inexpensive to manufacture and convenient and 10 durable in operation. My invention aims also to produce a tester that may easily be manipulated on a jacquard attachment for flat knitting machines or for other knitting machines adapted to knit jacquard patterns 15 into fabrics, the purpose being to provide such a device which may be readily used to obtain quick results in the matter of selecting and experimenting with designs intended to be knitted into the fabric.

20 In the accompanying specification I shall describe, and in the annexed drawing show, an illustrative embodiment of the present invention. It is, however, to be clearly understood that my invention is not limited 25 to the specific form thereof herein shown and described for purposes of illustration only.

Referring to the accompanying drawing illustrating the aforesaid illustrative embodiment of the present invention:

30 Fig. 1 is a plan view of said embodiment showing the testing fingers in closed position;

Fig. 2 is an end view of the same showing the device mounted upon the jacquard attachment or jacquard knitting machine;

Fig. 3 is a cross-sectional view of said embodiment showing the device mounted upon the jacquard attachment or jacquard knitting machine shown in Fig. 2 of the drawing; 40 and

Fig. 4 is a view similar to Fig. 1 showing the testing fingers in open position.

Referring now to the aforesaid illustrative embodiment of the present invention, and more particularly to the drawing illustrating the same, the jacquard tester comprising the aforesaid illustrative embodiment of the present invention consists of a frame generally indicated by reference character 10 and

having the end portions 11 and 12 and the side portions 13 and 14.

The end portions 11 and 12 have the up-standing members 15 and 16 at each end thereof, as shown more clearly in Fig. 1 of the drawing, for the purpose of forming bearings for the shafts 18 and 17. Mounted upon the shafts 18 and 17 are banks of testing fingers 19 and 20, respectively. The fingers 19 are pivotally mounted on the shaft 18, 60 while the fingers 20 are pivotally mounted on the shaft 17. The fingers 19 and 20 are held against lateral movement with respect to the shafts 18 and 17, respectively, by means of the sleeves 21 and 22 at the ends of the shafts 65 18 and 17, respectively. These shafts are secured in the bearings 15—16 respectively by means of the bolts 23—24 which are secured into the ends of the shafts 17—18 respectively, lock nuts 25 and 26 being provided 70 for securing the parts in place.

Mounted upon the shaft 18 is a bracket 27 which is held firmly in place on the shaft 18 between the nuts 24 and the lock nuts 26, 75 as shown more clearly in Fig. 4 of the drawing. The purpose of the bracket 27 will be made more clear later on in this specification.

It will be noted, by referring to Figs. 2 and 3 of the drawing, that the side pieces 80 13 and 14 are beveled, as shown at 28. The purpose of this is to enable the tester to fit snugly over the jacquard roller, which, in the form here shown in the drawing and illustrated by way of example merely, is substantially hexagonal in cross section. This arrangement tends to hold the tester rigid while the jacquard roller, here designated by reference character 30, carries the tester up to the needles or needle helpers of the jacquard knitting machine or of the jacquard attachment, both being preferably of the flat knitting machine type.

It will be noted, from a careful inspection of Figs. 1 and 4 of the drawing, that the testing fingers 19 are offset or staggered with respect to the fingers 20. Preferably, the degree of this offset or staggered relation corresponds to one-half of the width of one of the fingers 19 or 20. It may here also be 100

stated that each of the fingers 19 and 20 corresponds to one of the needle helpers or needles of the flat knitting machine bed or auxiliary bed, as the case may be. More particularly, 5 each of the fingers 19 corresponds to the needle helpers or needles in one row or course, while each of the fingers 20 corresponds to another row or course of needle helpers or needles. That is, the tester 10 of the present invention is designed to be used in conjunction with a flat knitting machine or attachment adapted to knit jacquard patterns, and has the pattern card engaging ends of the needle helpers or sinkers mounted in staggered relation with respect 15 to each other. That is, the pattern card engaging end or butt of one needle helper or sinker is higher than the pattern of the needle helper or sinker next to it, so that when the 20 tester is mounted upon the jacquard roller and is brought up into operative engagement with the pattern card engaging ends or butts of the needle helpers or sinkers, the fingers 19 will be adapted to engage the butts or ends 25 of one set of needle helpers or sinkers, such as the upper set, while the fingers 20 will be adapted to engage the ends or butts of the remaining set of needle helpers or sinkers, such as the lower set. 30 Assuming now that the tester of the present invention is to be used in connection with the types of knitting machines and attachments described above, that is, the types of knitting machines in which the pattern card 35 engaging ends or butts of the needle helpers or sinkers are staggered, and which therefore permits the convenient arrangement of approximately 18 or even more needles to the inch instead of only about 9 needles to the 40 inch as heretofore, it will be noted that the side members 13 and 14 bear a scale on which, from the zero center, the needles are numbered according to even numbers in groups of five each, these groups being themselves numbered 45 1, 2, 3, 4 and 5 outwardly from the zero center, as clearly shown in Fig. 4 of the drawing. Similarly, the side member 14 bears a scale in which the units are numbered according 50 to odd numbers, 1, 3, 5, 7 and 9, and are arranged in groups of five units to either side of the center line, these units themselves being numbered 1, 2, 3, 4 and 5. By this arrangement each of the fingers 19 and 20 has a number, left or right, in a particular group, 55 the fingers on the side member 13 being characterized by the even numbers and the fingers on the side member 14 being characterized by the odd numbers on their respective scales. By means of this arrangement any desired 60 pattern may be diagrammatically or schematically indicated by a series of numbers, the even numbers for a given stitch corresponding to the operative or inoperative fingers 19 which in turn correspond to the upper pattern card engaging butts or ends of 65

the needle helpers or sinkers, while the odd numbers correspond to the operative or inoperative fingers 20 which in turn correspond to the lower pattern card engaging butts or ends of the remaining course or row of needle helpers or sinkers. 70

When now it is desired to use the tester, the operator or designer, wishing to determine how an experimental or test design would look when knitted into the fabric, 75 places the tester upon the jacquard roller 30 in the manner illustrated in Figs. 2 and 3 of the drawing. For this purpose the jacquard roller 30 is provided with the parallelly arranged grooves 31 and 32 disposed longitudinally thereof. The jacquard roller 30 also has a central boss 33, which has a series of small holes 34 therein, to permit the pins 35, mounted on the end pieces 11 and 12 of the tester, to be inserted therein. The purpose 80 of this arrangement is to permit the operator or designer to position the tester upon the jacquard knitting machine or attachment in such a way as to bring the fingers of the tester into proper alignment with the staggered pattern card engaging butts or ends of the needle helpers or sinkers in the bed or auxiliary bed of the knitting machine or attachment. 90

The operator or designer then selects some portion of the jacquard roller 30, which roller is considerably longer than the tester, and places the tester upon such selected portion of the jacquard roller. After this is done he throws down, into the position indicated in 95 Fig. 3 of the drawing, a predetermined arrangement of the fingers 19 or 20, according to the diagram or scheme which he has previously prepared for this purpose. This is so that such selected fingers may be brought 100 into operative relation with the pattern card engaging butts or ends of the needle helpers or sinkers selected for the particular portion of the pattern now being tested, when the jacquard roller is thrown forward into operative position against the pattern card engaging butts or ends of the knitting machine or attachment. 105

When the selected fingers on the tester are thrown down, as shown in Fig. 1 of the drawing, those fingers that have been thrown down will strike the pattern card engaging ends or butts of the needle helpers and advance the needles in the knitting machine so as to produce a certain design upon the fabric to be knitted. The fingers that were left in the out or open position, as shown in Fig. 1 of the drawing, will, of course, not strike the needle helpers and will therefore not operate the needles of the knitting machine, so that the latter will just continue to make plain knitted fabric while the fingers that are open, as shown in Fig. 1 of the drawing, will advance the needles to form a part of the jacquard design. When the fingers are put 110 115 120 125 130

in the position as shown in Fig. 4 of the drawing, and the tester is brought forward upon the jacquard roller against the pattern card engaging ends or butts of the needle helpers, the pattern card engaging ends of the needle helpers will enter the longitudinal grooves 31 and 32 of the jacquard roller and will therefore not be operated to actuate any needles.

Accordingly, by the operation of certain of the fingers 19 and 20 into the out position as shown in Fig. 4 of the drawing, leaving certain selected fingers 19 and 20 in the down position as shown in Fig. 1 of the drawing, the designer or operator may thus test or check a pattern which he has schematically outlined by means of the key numbers corresponding to the various fingers. After the operator or designer has tested the experimental design and has determined that the same is desirable, it is only necessary for him to indicate according to their respective numbers the positions of the operative fingers 19 and 20 corresponding to each row or course of loops of the design to be knitted, from which numbers the permanent pattern cards may be made. It will, of course, be obvious that the pattern cards, which do not form a part of the present invention but are more fully set forth and are claimed in another copending application filed September 24, 1924, Serial No. 739,481, and entitled "Card for jacquard knitting machine" will have two rows of perforations defining the two corresponding rows of webs or solid portions for engaging the desired butts or ends of the needle helpers, corresponding to the down positions of the fingers 19 and 20 during the experimental test or run of the pattern.

The device of the present invention possesses great advantages in that it is exceedingly simple in construction, durable in use and very convenient to operate. It enables the ready and convenient determination of the pattern which it is desired to check and thus enables the ready and certain manufacture of the cards which are to be made corresponding to the final pattern selected.

What I claim as my invention is:

1. A master testing device for jacquard knitting machines and the like, comprising, in combination, a substantially rectangular frame comprising end and side members, and a set of testing fingers pivotally mounted on each of said side members.

2. A master testing device for jacquard knitting machines and the like, comprising, in combination, a substantially rectangular frame comprising end and side members, and a set of testing fingers pivotally mounted on each of said side members, the testing fingers of one set being offset with respect to the testing fingers of the remaining set.

3. A master testing device for jacquard knitting machines and the like, comprising,

in combination, a substantially rectangular frame comprising end and side members, a set of testing fingers pivotally mounted on each of said side members, whereby selected ones of the testing fingers of each set may be pivoted into operative position and the remaining testing fingers of each set left in inoperative position, and means for supporting the operatively conditioned testing fingers of one set in upraised position with the operatively conditioned testing fingers of the other set in downward position.

4. A master testing device for jacquard knitting machines and the like, comprising, in combination, a substantially rectangular frame comprising end and side members, a set of testing fingers pivotally mounted on each of said side members, the testing fingers of one set being offset with respect to the testing fingers of the remaining set, whereby selected ones of the testing fingers of each set may be pivoted into operative position and the remaining testing fingers of each set left in inoperative position, and means for supporting the operatively conditioned testing fingers of one set in upraised position with the operatively conditioned testing fingers of the other set in downward position.

5. A master testing device for jacquard knitting machines and the like, comprising, in combination, a substantially rectangular frame comprising end and side members, and a set of testing fingers pivotally mounted on each of said side members, and a characteristic scale associated with each set of testing fingers to designate the individual fingers of the particular set.

6. A master testing device for jacquard knitting machines and the like, comprising, in combination, a substantially rectangular frame comprising end and side members, and a set of testing fingers pivotally mounted on each of said side members, the testing fingers of one set being offset with respect to the testing fingers of the remaining set, and a characteristic scale associated with each set of testing fingers to designate the individual fingers of the particular set.

7. A master testing device for jacquard knitting machines and the like, comprising, in combination, a substantially rectangular frame comprising end and side members, a set of testing fingers pivotally mounted on each of said side members, whereby selected ones of the testing fingers of each set may be pivoted into operative position and the remaining testing fingers of each set left in inoperative position, means for supporting the operatively conditioned testing fingers of one set in upraised position with the operatively conditioned testing fingers of the other set in downward position, and a characteristic scale associated with each set of testing fingers to designate the individual fingers of the particular set.

8. A master testing device for jacquard knitting machines and the like, comprising, in combination, a substantially rectangular frame comprising end and side members, a set of testing fingers pivotally mounted on each of said side members, the testing fingers of one set being offset with respect to the testing fingers of the remaining set, whereby selected ones of the testing fingers of each set 10 may be pivoted into operative position and the remaining testing fingers of each set left in inoperative position, means for supporting the operatively conditioned testing fingers of one set in upraised position with the operatively conditioned testing fingers of the other set in downward position, and a characteristic scale associated with each set of testing fingers to designate the individual fingers of the particular set.
- 20 In testimony, whereof, I have signed my name to this specification this day 30th of October, 1924.

FRANK HUG.
